CLOSURE

Melvin H. Best and Charles B. Le Bon, III, Pasadena, Calif., assignors to Arcadia Metal Products, Arcadia, Calif., a corporation of California

Application June 5, 1950, Serial No. 166,208

2 Claims. (Cl. 189—64)

1

This invention is concerned with closures and more particularly provides improvements in prefabricated closures having slidable panels.

The prefabricated closure of the invention has an all metal construction, save for possibly the panes, which eliminates all possibility of warpage and consequent troublesome and incorrect alignment of sliding and stationary members.

For easy operation of a closure having a sliding panel, it is highly important that the individual members of the closure be accurately fabricated and correctly assembled. Furthermore, it is desirable that the closure be so constructed that when installed the panels may be readily removed for the replacement of broken panes.

The closure of the invention is relatively inexpensive to fabricate, easily installed and may be readily disassembled, repaired or adjusted. It lends itself to mass manufacture, for it is built of a minimum number of rolled steel sections which give an exceptionally strong and sturdy construction. The jambs and head of the closure frame are of like construction as are certain panel members, thus lessening the cost of manufacture.

In preferred practice, the frame of the closure is completely assembled at the factory and shipped to the installation site in this condition. The sash or panel is shipped in a knocked down condition, assembled near the site and installed after the frame is in position in the wall.

Generally speaking, the panel or sash of the closure of the invention includes a bottom cross member having a groove on its upper inside face and a groove on its bottom face. We prefer to fabricate this member by rolling a sheet into an H section. In our preferred embodiment, there is a double thickness of the sheet on the sides of the top groove and a single thickness of the sheet on the sides of the bottom groove. A pane is mounted in the upper groove of the member.

Each mullion or upright member of the panel is manufactured by rolling a sheet into a U section, forming a longitudinal groove extending the length of the inside face of the mullion. We prefer to fasten the mullions at their lower ends to opposite ends of the bottom cross member by sheave or roller brackets which are disposed at the bottom corners of the panel within the bottom groove of the bottom member and in the grooves of the mullions. Sheaves are rotatably mounted within the brackets about axes transverse to the main plane of the panel.

The frame of the closure of our invention in-

cludes a head and two jambs. Each member has two elongated channels running the length of its inner face and is formed by bending a sheet so that in section it comprises two U's with a common center leg. All three legs of the U's are composed of a single thickness of the sheet. This construction gives an unusually sturdy and relatively inexpensive frame which is adapted to mass manufacture.

10 In one form of our structure, a track is mounted directly beneath one of the channels of the head on a sill which joins the lower ends of the jambs or as an alternative the track may be formed integrally with the sill from a metal sheet. The 15 movable panel when positioned in the frame rides on the track with the bottom groove of the lower cross member straddling the track and a top cross member of the panel engaging an elongated spring weatherstrip disposed in the overlying channel of the head. The sheaves engage the track within the bottom groove of the lower member. In one embodiment of the closure of our invention, we provide an elongated housing with an open bottom which is disposed in the bottom 25 groove and which encloses the sheave brackets and sheaves. The lower portion of the housing is constricted to engage slidably opposite sides of the track.

A stationary panel is mounted in the other 30 channel or in an alternative, with the provision of a second track spaced from and parallel to the first track, a second movable panel may be used.

The closure of our invention will be more clearly understood in light of the following detailed description and accompanying drawings. 35 The description and drawings are directed to a window but it is evident that many of the features described and illustrated are applicable to a door.

40 Fig. 1 is a front elevation of a presently preferred form of a window of our invention, having a sliding and a stationary sash;

Fig. 2 is a fragmentary horizontal section of the window of Fig. 1 taken along line 2—2, showing two interlocking baffles which close the passageway between the two spaced sashes;

45 Figs. 3 and 4 are fragmentary cross sections of the window of Fig. 1 taken respectively along lines 3—3 and 4—4. In Fig. 3 the movable sash of Fig. 1 is now shown;

50 Fig. 5 is a fragmentary elevation of the sliding sash of the window of Fig. 1, showing in particular the manner of joining the corners;

Fig. 6 is a fragmentary end view of the sliding 55 sash of the window illustrated in Fig. 1;

Fig. 7 is a fragmentary cross section of a modified form of the window illustrated in Fig. 1, the section being taken through the middle of the window and illustrating in particular a rubber saddle seal and rubber block;

Fig. 8 is a fragmentary cross section of the modified window of Fig. 7;

Fig. 9 is a side elevation of a sheave bracket employed in the modified window of Fig. 7, and showing the position of the saddle seal relative to the bracket;

Fig. 10 is a fragmentary horizontal section of the modified window illustrated in Fig. 7; and

Fig. 11 is a cross section of a modification of the head and the jambs illustrated in Figs. 2, 3 and 4.

As shown in Fig. 1, the window is made up of a rectangular frame 11, with a movable panel or sash 12 and a stationary panel 13, both mounted in the frame.

The frame comprises a sill 16, a top horizontal member or head 17, and two upright members or jambs 18, 19 connected respectively to opposite ends of the sill and head.

The two jambs and the head are similar in construction. Each of the jambs and the head has two parallel channels 22, 23 running the length of the inner face of each member and a flange 24. Each member is integrally formed of a single sheet of steel so rolled that in cross section it comprises two U's with a common center leg. All three legs of the U's are composed of a double thickness of the sheet, with the bases of the U's having a single thickness. The flange which is on the inner side of the window frame is formed by extending an outer thickness of one of the outer legs rearwardly of the bases of the U's.

In an alternative, the jambs and the head may be constructed as shown in Fig. 11. In this alternative, the rearwardly extending flange is on the outer side instead of the inner side of the window and is formed as before by extending an outer thickness of one of the outer legs rearwardly of the bases of the U's. The outer thickness of the other one of the outer legs is extended rearwardly a short distance to form a stop 25 for plaster.

As shown in Figs. 3 and 4 the sill, which also is made of a rolled piece of steel, has a top sill section 26 which slopes downwardly from the inner to the outer side of the window and two downwardly extending flanges 27, 28 formed integrally with the sill section.

The stationary sash or panel (see Figs. 2, 3) has an upper cross member 30, a lower cross member 31 of irregular cross section, and two mullions 35, 36 which are fastened respectively to opposite ends of the lower and upper members. A pane of glass 37 is held in a circumferential groove on the inner edge or face of the sash formed of the cross members and mullions.

The two mullions and the upper cross member are each fabricated from a sheet of steel rolled into a U section with the ends of the legs of the U folded in upon their respective sides. The legs and bases of the U define the groove holding the pane of glass.

The lower cross member 31 is integrally formed of a steel sheet shaped to have an open sloping bottom, a relatively long first side 39 lying in a plane parallel to the plane of the pane, and a shorter second side 40 spaced from and parallel to the first side. A top portion 41 having a

longitudinal groove joins the upper ends of the first and second sides. A third portion 42 extends perpendicularly and outwardly from the lower end of the second side. A short flange 43 extends downwardly from the outer end of the third portion. The lower end of this flange defines the upper side of the sloping bottom. A second flange 44 extends inwardly from the lower end of the first side in the plane of the bottom side.

The third portion and the first flange of the bottom member form a raised step through which several screws 46 pass, fastening the stationary sash to the sill. The end 46A of the raised step adjacent to the middle of the window is closed, thus preventing the flow of rain along the sill between the stationary and movable panels.

An elongated baffle 49 (Fig. 2) is held to the outer face of the mullion 35 by a double thickness member 50 and a screw (not shown). The baffle extends at an angle from the mullion toward the movable sash and the jamb 19. This baffle interlocks with a similar baffle 79 of the closed movable sash, thereby blocking the passageway between the spaced sashes.

Four elastic seals 52 of U-shaped cross section are disposed respectively in the grooves of the inner edges or faces of the four sides of the stationary sash, with the base of the U abutting the bottom of the groove and with the legs of the U extending about halfway up the sides of the groove. These seals may be extruded from rubber or other elastomer. The seals of the mullions and of the upper member are retained in their respective grooves by the folded-in portions of the mullions and upper member, i. e. the ends of the legs of the seals about the ends of the folded-in portions of the mullions and upper member.

A mastic seal 53 may be placed over the rubber seals to further assure that the sash is weathertight.

The mullions and the top member may be formed integrally and mitred at the corners, leaving a metal connection, which is bent until the mitred edges fit together. However, we prefer to join the mullions and the top member of the stationary panel with clips 78 (as shown in the movable panel of Fig. 5) which are sprung right angled members having tits 78A, which are sprung into place in holes in the adjacent members at the corners. The lower member is fastened at both of its ends to the mullions by two brackets 70 (only one shown in Fig. 5) which are disposed inside of the member, with an end of each bracket extending into the groove of the adjacent mullion. A screw 73 fastens each mullion to its associated bracket and two seals 71 hold the lower member to the bracket.

The movable panel or sash (see Figs. 2, 4) is made up of a lower cross member 55, an upper cross member 56, and two mullions 58, 59 which are fastened respectively at opposite ends of the lower and upper members.

The mullions and the upper member of the movable sash have the same cross sections and are each formed of sheets of rolled steel as their counterparts in the stationary panel. The mullions of the movable sash have slots 60 (see Fig. 6) at their lower ends which permit the straddling of a track 61 by the mullions, when the sash is slidably mounted thereon.

The lower cross member is formed integrally from a sheet of steel rolled into an H-section, so that it has top and bottom longitudinal grooves 62, 63. There is a double thickness of the sheet

on the sides of the top groove and a single thickness on the sides of the bottom groove.

The movable sash, like the stationary sash, has a circumferential groove encircling its inner edge and in which there are disposed four elastic channel shaped seals 65. The seals are identical with those of the stationary panel and are retained in the grooves of the upper member and the mullions by the folded-in portions of the sides of these members. A pane of glass 66 is mounted in the seals, with mastic 67 forming a further seal.

Two sheave or roller brackets 79 (only one shown) are disposed respectively at the lower corners of the movable sash (see Fig. 5) inside the bottom groove of the lower cross member and inside the grooves of the respective mullions. Each bracket is fastened to the cross members by two screws 71, whose heads lie on the bottom of the groove on the inner face of the bottom member. Each mullion is fastened to its adjoining sheave bracket by a single screw 73 which extends through the mullion and a threaded hole of a lug 75 of the sheave bracket. Each lug is an extension of the top of the bracket, bent downwardly over an open end of the bracket. Each lug is just short of reaching the bottom of the groove of the adjacent mullion.

A sheave 76 is rotatably mounted within each bracket with its axis of rotation transverse to the bottom groove of the lower cross member.

The sheave brackets have a two fold purpose:

Each bracket serves to hold one of the mullions to the bottom horizontal member. Secondly, the sheave brackets when fastened to their respective mullions and to the lower horizontal member, hold the sash on the track.

The mullions of the movable sash are fastened at their upper ends to the upper cross member by the clips 78, L-shaped with the ends of the legs of the L bent inwardly to form the tits 78A (Fig. 5). Each clip is placed around an upper corner of the sash, with the tits respectively inserted into two holes in the outer faces of the upper member and one of the mullions.

The movable sash has a baffle 79, similar to that of the stationary sash, which is affixed to the mullion 59 and extends at an angle from the mullion toward the other sash. With the movable sash in the far left position as shown in Figs. 1, 2, the two baffles interlock and form a weathertight seal.

The stationary sash is held in an upright position in the front channel 22 of the head and the jamb 19 by two elongated spring weatherstrips 81, 82. The weatherstrips are made of stainless steel and each has a cross section of a U with diverging legs. The outer ends of the legs are folded outwardly and rearwardly. The weatherstrips are disposed in their respective channels, with the base of the U abutting the bottom of the channel and the folded portions of the legs resting against the sides of the channel. The weatherstrip of the head only extends from the jamb 19 to a point slightly beyond the middle of the frame, i. e. only as far as the stationary sash extends.

The movable sash is slightly mounted on the track 61 of a guide member 83 which is fastened to the sill parallel to the stationary sash by several screws 84 which pass through a base 85 of the guide. The guide member is integrally formed from a piece of stainless steel, with the base of the guide having a double thickness of

the sheet for a portion of its width. The edge of the lower thickness abuts an elongated bead 26A of the sill. The bead together with the lower thickness assures that the guide will be correctly positioned on the sill. The track lies directly beneath the channel 23 of the head. The movable sash when positioned in the frame rides on the track with its top cross member slidably engaging a spring weatherstrip 86 in the channel 23 of the head and when in the closed position, the mullion 58 of the sash engages a spring weatherstrip 87 of the jamb 18.

The track extends longitudinally through the bottom groove of the lower cross member and the slots of the mullions, with the rotatable sheaves 15 engaging the track. The track has a horizontal flange 90 which in conjunction with an adjacent inwardly extending flange 91 of the lower cross member of the movable sash provides a further weather seal.

The movable panel can be slid along its track from one end of the frame to the other. It should be noted that the weatherstrip of the head not only serves as a seal, but also as a friction lock for holding the movable panel wherever it is placed along the track.

The window is installed in a structure in the following manner. The frame alone is first positioned in a wall of the structure. The sashes are 30 assembled in a glazier's shop as described above. The several weatherstrip members may be placed in the frame at the factory or at the site after the frame is placed in the wall.

Next the mullion 36 and the upper member of 35 the assembled stationary sash are inserted into channels 22 of the head and jamb, and with the fastening of the lower member of this sash to the sill by the several screws 46, the sash is rigidly and correctly positioned in the frame.

40 The sliding sash and guide member are simultaneously placed in the frame. The lower member of the assembled sash is placed astraddle the track of the guide member with the sheaves 35 engaging the track. The upper member of the assembled sash is inserted in the channel 23 of the head, and the guide member with the sash mounted thereon is forced into its proper position on the sill with the lower thickness of the 45 base of the guide abutting the bead of the sill. The base of the guide is then fastened to the sill by several screws 84. Both panels may be readily removed from the frame by simply removing the several mounting screws.

45 A modification of the window of our invention is illustrated in Figs. 7 and 8. The window is similar to that described above with several modifications which give a more weather-proof window. Only the features differing from the window of Figs. 1 to 6 are described.

60 In the modified window, a track 100 and sill 101 are integrally formed from a sheet of rolled steel. The track is covered with an elongated cap 103 of stainless steel to forestall corrosion.

An elongated weatherstripping housing 105 65 with an open bottom (Fig. 8) is disposed in a lower groove 106 of a bottom cross member 107 of a movable sash 109. The lower portion of the housing is constricted to engage slidably opposite sides of the track cap within the lower groove. This housing encloses two sheave brackets 110 and their sheaves 112.

The sheave brackets (Fig. 9) differ from those of the window of Fig. 1, in having two opposite longitudinal slots 114 in the sides of the bracket. Each of two saddle members 115 has a head 117

(Figs. 7 and 9) which is inserted into the two slots of one of the brackets with the bottoms of two longitudinal recesses 118 of the saddle engaging the inner walls of the sheave bracket. The unenclosed end of each saddle member abuts the bottom of the inside groove of its adjacent upright mullion. Each saddle member has two downwardly extending and spaced legs 120, 121 of unequal length which straddle and seal around the track cap. The elongated housing does not enclose the two saddle members but extends the length of the groove between these members, the saddle members sealing the opposite ends of the housing.

The stationary sash (Fig. 8) of the modified window differs from that described before in that its lower cross member is made up of two rolled steel pieces 130, 131 which are fastened together and in that it has no portion comparable to the raised step (defined by the portion 42 and the flange 43 of the stationary sash, Fig. 3). The piece 130 has the cross section of an H with relatively long lower legs. The lower legs are of unequal length so that when the stationary sash is affixed to the sloping sill it will be in a vertical plane. The other piece 131 is formed of a steel sheet so bent that when placed on the sloping sill it has a vertical leg 133 which is fastened to the inner wall of the shorter leg of the first piece and a second longer leg 134 which extends from the shorter leg of first section along the sill to the bottom of the track. The stationary sash is held to the sill by several screws 135.

The raised step of the window illustrated in Figs. 1 and 3 prevents the flow of moisture along the sill between the two spaced sashes. In the modified window, a rubber block 137 is fastened to the midsection of the sill between the spaced sashes (Fig. 10 shows the position of the block relative to two interlocking baffles 140, 141 of the closed sashes). The block has a sloping bottom of the same angle as the sill so that when the block is affixed to the sill its upper side lies in a horizontal plane. The end of one leg of the track cap abuts the top of the block adjacent the track (Fig. 8).

As shown in Fig. 7, the longer leg of the saddle member at the baffle end of the closed slideable sash engages the upper side of the block. The lower ends of the two locked baffles (Fig. 10) seal against the top of the rubber block, thereby completely enclosing the passageway between the two spaced sashes. To assure a positive seal between the baffles of our modified window, we provide an elongated thin springy metal strip 143 which is compressed by and between the two locked baffles as shown in Fig. 10. The strip is held to an upright mullion 144 of the stationary sash by the baffle 140.

The modified window is installed in a structure in a manner similar to that described above, with the sashes being first assembled in a glazier shop. Preferably, the stationary panel is first positioned in the frame, and the rubber block next secured to the sill. The cap is then positioned on the track with one of its legs abutting

the top of the block. And as a last step of the installations, the movable sash is positioned in the frame.

We claim:

- 5 1. In a closure panel, the combination which comprises integral mullions formed from sheets rolled into U sections so that the mullions have longitudinal grooves on their inside faces, a bottom cross member formed integrally from a sheet rolled into an H section so that it has top and bottom longitudinal grooves, roller brackets disposed respectively at the lower corners of the panel inside the bottom groove of the cross member and inside the grooves of the respective mullions, the bottom member being fastened to the mullions by the brackets, and rollers disposed respectively in the brackets and rotatable about axes transverse to the main plane of the panel.
- 10 2. In a closure panel, the combination which comprises mullions formed integrally from sheets rolled respectively into a U section with the ends of the legs of the U folded in upon their respective legs, so that the mullions have longitudinal grooves on their inside faces, a bottom cross member formed integrally from a sheet rolled into an H section, so that it has top and bottom longitudinal grooves, there being a double thickness of sheet on the sides of one of the grooves and a single thickness of sheet on the sides of the other groove of the cross member, seals having U-sections and respectively disposed in the grooves of the mullions and in the top groove of the bottom member, the seals disposed in the mullions being of such size that the ends of their respective legs abut the ends of the folded in portions of the mullions, sheave brackets disposed respectively at the lower corners of the panel inside the bottom groove of the lower member and inside the grooves of the respective mullions, the bottom member being fastened to the mullions by the brackets, and sheaves disposed respectively in the brackets and rotatable about axes transverse to the main plane of the panel, and a pane mounted in the several seals.
- 15 30 35 40 45
